(57) **CLAIM**

The ornamental design for a tire tread for a vehicle tire, as shown and described.

DESCRIPTION

FIG. 1 is a perspective view of a tire tread for a vehicle tire, showing our new design;

FIG. 2 is a front elevational view thereof;

FIG. 3 is a right side elevational view thereof;

FIG. 4 is a left side elevational view thereof; and,

FIG. 5 is an enlarged partial front view thereof.

The vehicle tire pattern is repeated uniformly around the circumference of the tire structure. The dash-dot lines showing the boundaries of the illustrated detail and the broken lines depicting the sidewall of the tire do not form part of the claim.
